UNITED STATES PATENT OFFICE.

ARTHUR E. COUPAL, OF SOUTH BOSTON, MASSACHUSETTS, ASSIGNOR TO BUFFALO SHOE CO., OF BUFFALO, NEW YORK, A CORPORATION OF WEST VIRGINIA.

STAPLE.

1,039,103.

Specification of Letters Patent. Patented Sept. 24, 1912.

Application filed November 15, 1911. Serial No. 660,362.

To all whom it may concern:

Be it known that I, ARTHUR E. COUPAL, a citizen of the United States, residing at South Boston, in the county of Suffolk and 5 State of Massachusetts, have invented new and useful Improvements in Staples, of which the following is a specification.

This invention relates to improvements in staples and particularly to those adapted 10 for use in the manufacture of boots or shoes to fasten a welt or rand to an insole or an outer sole to an inner sole or to a welt. In work of this character, it is often desirable that the staple should be placed very close 15 to the edge of the sole and yet it should not project to said edge, otherwise it would interfere with the trimming thereof. It is also desirable that in clenching the staple in a soft material, like leather, that the ends 20 should turn inwardly from the edge of the sole in order to obtain a firmer hold therein and to prevent the breaking out of the leather between said staple and the edge of said sole, and again in making a waterproof 25 shoe it is necessary that the staples be placed close together in order to prevent water from leaking through the cracks, and to do this the legs of said staples must be so clenched that they will not interfere with 30 the legs of the staples adjacent thereto.

The object of the invention is, therefore, to provide a staple which may be manufactured at a minimum cost in very few operations and being so formed in its manufacture 35 that, when driven against a flat anvil, the extremities of the legs thereof are bent toward each other and laterally thereof on one side of a plane passing longitudinally through the body of said staple, thereby 40 producing a staple which is adapted to meet the above requirements.

The invention consists in the combination and arrangement of parts set forth in the following specification and particularly 45 pointed out in the claim thereof.

Referring to the drawings: Figure 1 is an elevation of a staple embodying my invention. Fig. 2 is an elevation of the same as viewed from the right of Fig. 1. Fig. 50 3 is a section taken on line 3—3 of Fig. 1. Fig. 4 is an elevation of the staple as it would appear after the clenching of the same. Fig. 5 is a plan view of a portion of a shoe sole having several staples clenched 55 therein. Fig. 6 is a detail section taken on

line 6—6 of Fig. 5. Fig. 7 is a perspective view of the staple embodying my invention.

Like numerals refer to like parts throughout the several views of the drawings.

In the drawings, 8 is a staple having legs 60 9 and 10 formed thereon and provided with faces 11 and 12 substantially parallel to each other and oblique to a plane passing longitudinally through the body of said staple and containing the median axle line 65 of the wire constituting the legs of said staple, said faces being located upon the same side of said plane and terminating at one side of said plane. Upon the legs 9 and 10 in addition to the faces 11 and 12 70 are surfaces 13 and 14 oppositely disposed on the outer edges of said legs adjacent to their extremities and inclined toward each other and toward a longitudinal plane extending laterally of said first mentioned 75 longitudinal plane.

One of the particular advantages secured by the construction hereinbefore described is that in the manufacture of said staple but few operations are required to form the 80 same, the wire which forms the blanks being preferably severed from a continuous piece of wire by a cutter which in one operation cuts diagonally across said wire forming the oblique face 11 and the oppositely inclined surfaces 13 and 14. The next operation is to form the other oblique 85 face 12 which is accomplished in a single operation by bending the blank, the final operation being to bend the blank to form the 90 legs 9 and 10 which completes said staples and leaves it in a condition to be driven into the work.

As an example of the many uses to which said staple may be put, I have illustrated in 95 Figs. 5 and 6 the same driven into the toe of a boot. The staple 8 is driven along suitable guides and into the sole 15 and welt 16 with the oblique faces 11 and 12 toward the edge of said sole, until the faces 11 and 100 12 co-operating with the surfaces 13 and 14 engage a flat face 17 of an anvil 18, whereupon the extremities of the legs 9 and 10 are forced inwardly away from the edge of said sole and toward each other. The positions 105 of said extremities with relation to each other permit the staples to be placed as close together around the toe of a boot as on the sides thereof without the legs of one of said staples interfering with those of adjac- 110

cent staples and also permitting said staples to be placed very near to the edge of said sole and still securing a firm hold therein.

It will be noted that with a staple of the 5 character hereinbefore described no recesses are required in the anvil to turn the extremities in the proper directions as the beveled faces thereon are adapted to govern this, thus making said staple better adapted for 10 use in boots or shoes, for, where a recess has to be employed the surface of the leather bearing thereagainst is apt to be roughed up or injured owing to the yielding surface thereof being pressed into said recess.

15 Having thus described my invention, what I claim and desire by Letters Patent to secure is:

As an article of manufacture, a staple with two legs having parallel faces adjacent to the extremities of said legs, oblique

20 to a plane passing longitudinally through the body of said staple, and containing the median axial line of the wire constituting the legs of said staple, said faces terminating at one and the same side of said plane, 25 said legs also having outer oppositely disposed surfaces inclined toward a longitudinal plane extending laterally of said first mentioned longitudinal plane, whereby when said staple is driven against a flat anvil the extremities of said legs are caused to turn toward each other and laterally of and on the same side of said longitudinal plane.

25 In testimony whereof I have hereunto set my hand in presence of two subscribing witnesses.

ARTHUR E. COUPAL.
